UNITED STATES PATENT OFFICE.

HORACE F. GRUMAN, OF JACKSON, MICHIGAN, ASSIGNOR TO GRUMAN SPECIAL MACHINE COMPANY, OF JACKSON, MICHIGAN.

FLAT-FELL SEWING MACHINE.

Application filed August 10, 1922. Serial No. 580,891.

To all whom it may concern:

Be it known that I, HORACE F. GRUMAN, a citizen of the United States of America, residing at Jackson, in the county of Jackson and State of Michigan, have invented certain new and useful Improvements in Flat-Fell Sewing Machines, of which the following is a specification, reference being had therein to the accompanying drawings.

10 This invention relates to sewing machines and more particularly to a sewing machine which will produce, with a single passage of material through the machine, what is known as a flat or French fell seam, and 15 the object of this invention is to embody in a sewing machine, mechanism for producing a seam of this character, which mechanism shall be a part of the machine, as distinguished from an attachment for 20 machines of well known construction, and whereby such mechanism may be located beneath the cloth plate of the machine to operate automatically and efficiently and where such mechanism will not interfere 25 with an accurate placing and guiding of the material or obstruct the operator's view of the work.

A further object is to produce a seam of this character in such a manner that the 30 folded over portion of the seam will lie at the underside of the material while being sewed and thus the finished or outer side of the material will be uppermost during sewing, with the folded portion of the 35 seam at the inner side of the work.

It is also an object to provide a flat fell 40 machine wherein the construction is such that only the usual vertical needle bar is located above the cloth plate, leaving this 45 plate as unobstructed as in the ordinary sewing machine for the free passage of the cloth thereover, and all operating mechanism is concealed and positioned where it may be lubricated without danger of soiling the work.

A further object is to provide a horizontally operating straight needle for forming one line of stitching and to provide certain other new and useful features, all as 50 hereinafter more fully set forth.

With the above and other ends in view, the invention consists in the embodiment of stitching and folding means and means for operating the same, in a sewing machine with such mechanism located below

and concealed by the cloth plate of the machine, and also in certain other new and useful features in the construction, arrangement and combination of parts, all as hereinafter more fully described and particularly pointed out in the appended claims, reference being had to the accompanying drawings in which—

Fig. 1 is a front elevation of a machine 60 illustrative of the invention and showing portions broken away and in section to more clearly disclose the construction;

Fig. 2 is a horizontal section substantially upon the line 2—2 of Fig. 1;

Fig. 3 is a transverse vertical section substantially upon the line 3—3 of Fig. 1;

Fig. 4 is a transverse section substantially upon the line 4—4 of Fig. 2;

Fig. 5 is a perspective detail of the folder, throat plate and the stitching plate in assembled relation; and

Fig. 6 is a perspective detail illustrating a seam produced by the machine.

In the accompanying drawings, a machine for forming a flat fell seam has been 80 shown, but it will be understood that the same is merely illustrative of one form of construction and that stitching and folding mechanism may be combined with or embodied in other types or constructions of 85 sewing mechanisms and machines. The sewing machine proper, which is of an old and well known type, comprises a base or frame 1 which is provided with bearings for a horizontally extending main drive 90 shaft 2 upon the outer end of which is secured the usual drive pulley 3, and this base or frame is covered by a top or cloth plate 4 from which rises the usual hollow pedestal 5 having a laterally extending hollow arm 6 provided with a head 7 at its free end. Within suitable bearings in this head is mounted the usual vertical needle bar 8 carrying the vertically disposed needle 9 at its lower end, and a vertical reciprocation is imparted to this needle bar from a horizontal rock shaft 10 extending longitudinally within the arm 6 and connected in any suitable manner with the bar, as by an arm 11 on the shaft and a link 12 100 connecting the free end of the arm with the bar. Motion is transmitted to the rock shaft from the main drive shaft 2 through the hollow pedestal 5, by means of an eccentric 13 on the shaft 2 and a rod 14 110

attached at one end to an eccentric strap 15 and at its opposite end to the free end of an arm 16 on the rock shaft. A presser bar 17 is also mounted for vertical reciprocation in bearings in the head 7 and is provided with the usual presser foot 18 beneath which the work passes as it is being stitched by the needle 9, any suitable means including an arm 19 being provided for 10 operating this presser bar in the usual manner. Set within an opening in the cloth plate 4 beneath the presser foot 18 is the usual throat plate 20 having a series of longitudinal slots therein to receive the 15 toothed portions of the main cloth feeder or dog 21 for feeding the material in timed relation to the operation of the needle 9 which passes through an opening in the presser foot, an opening 22 in said throat plate, and through the cloth, co-operating 20 with the usual stitch forming mechanism (not shown) beneath the cloth plate to form a line of stitching. An up and down motion is imparted to this feeder 21 by a cam 25 23 on the main drive shaft 2 which cam is engaged by a yoke 24 carrying said feeder and pivotally connected at 25 to upwardly extending rocker arms 26 pivoted at their lower ends to the frame 1. These arms are 30 rocked forward and back, imparting a reciprocating movement to the feeder 21 during its rising and falling movement imparted thereto by the cam 23, by an eccentric rod 27 embracing an eccentric 28 35 on the shaft 2 at one end and adjustably connected at its opposite end to one of said rockers 26, by a pin 29 having a head engaged with and slideable within an undercut groove 30 in an arm 31 secured to the 40 pivot pin 32 upon which the rocker arms 26 are secured. The throw imparted to the rocker arms and thus the length of stroke of the feeder, may be readily adjusted by adjusting the pin 29 along the 45 groove 30, and as this motion is transmitted from the main drive shaft the feeder is operated in timed relation to the reciprocation of the needle 9.

All of the above described elements or 50 their equivalents are common in and essential to a sewing machine for forming a single line of stitching by means of a vertical needle.

Machines embodying the present invention are adapted to form seams of the character illustrated in Fig. 6 wherein the two pieces of cloth to be united by the seam are indicated at 31 and 32, and the respective folded edge portions of these pieces, at 55 60 65 70 75 80 85 90 95 100 105 110 115 120 125 130 135 140 145 150 155 160 165 170 175 180 185 190 195 200 205 210 215 220 225 230 235 240 245 9999

is formed by the vertical needle 9. The pieces must however, be first united by the line of stitching 37, this line being formed while the edge portions 33 and 34 are extending vertically downward, the folding 70

and formation of the second line of stitching 36 being accomplished immediately thereafter. The pieces of cloth to be united, are fed to the machine with their edge portions extending vertically downward as shown in dotted lines in Fig. 6, these edge portions being passed into a slot indicated in dotted lines at 38 in Fig. 2, which slot opens through the front edge of the cloth plate 4. A stitching plate 39 is set into an opening in the cloth plate at the forward end of the throat plate 20 with its upper surface flush with the upper surface of the cloth and throat plates, and this stitching plate has a downwardly extending flange 40 at one edge, which flange forms one side of said slot 38 and a backing or support against which the downturned edge portions of the cloth are pressed by a horizontally operated presser foot 41 adapted to press these portions firmly against said flange and hold them firmly while being stitched together by the line of stitching 37 which is formed by a horizontally reciprocating needle 42 carried by a horizontal needle bar 43 reciprocable in suitable bearings on the frame or base 1 beneath the cloth plate 4 and forwardly of the needle 9 in the direction of travel of the cloth through the machine. Reciprocation of this horizontal needle bar in timed relation to the operation of the vertical needle 9 and other moving parts of the machine, is effected by means of a worm 44 on the shaft 2, a worm gear 45 on a shaft 46 extending transversely of the shaft 2, and a crank and connecting rod 47 transmitting motion from said shaft 46 to said needle bar 43. This needle when reciprocated, passes through an opening in a horizontal feeder 48, an opening in the presser foot 41 and an opening in the flange 40 of the stitching plate, passing through the two downturned edge portions of the cloth near the underside of the cloth plate and cooperating with looper mechanism, hereinafter described, to form the line of stitching 37 which unites these edge portions prior to the folding of the same.

The presser foot 41 is carried by a presser bar 49 reciprocable in bearings in the frame 1 and a coiled spring 50 sleeved upon this bar normally exerts a pressure to hold the bar moved endwise and the presser foot pressed toward the flange 40 to clamp said edge portions of the cloth between it and said flange, and to operate this presser bar in timed relation to the operation of the needle 42 and other parts, against the action of said spring 50, a rocker 51 is pivoted at 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 3

52 intermediate its ends to the frame with the lower end of said rocker operatively connected to said presser bar 49 by means of a stud 53 on a bar 54 secured to and 5 carried by said bar, and the upper end of said rocker pivotally connected to the needle bar 43 by a link 54^a. Reciprocation of the needle bar will thus impart movement to the presser bar to move the same 10 against the action of its coiled spring and thus release the edge portions of the cloth so that the same may be fed into the machine past the needle by the feeder 48 which has a toothed edge portion 55 adapted to extend 15 over the upper end of the presser foot 41 and engage the cloth.

This feeder 48 is moved into and out of engagement with the cloth in timed relation to the sewing and other operations by attaching said feeder at one end to the end of a rod 56 by means of a pivot screw 57 and said rod is reciprocated in its bearings on the frame by means of a cam 58 on the shaft 46, which cam is engaged by a yoke 59 pivoted at 60 25 and provided with an arm 61 extending downwardly from its pivot with the lower end of said arm connected to the rear end of said rod 56 by a link 62.

In order to impart a feeding movement 30 to the feeder 48 or a swinging movement in the direction of travel of the cloth, a link 63 is pivotally attached at one end to the feeder, intermediate the ends thereof and at its opposite end to the upper end of one 35 of the rocker arms 26, as indicated at 64. The feeder 48 is therefore moved toward and from the flange 40 and also swung longitudinally thereof to effect an intermittent feeding movement to the feeder.

40 After the edge portions 33 and 34 of the cloth have been united by the stitching 37, these portions are folded laterally and upwardly against the underside of the part 31 of the cloth, the edge portion 35 of the 45 portion 34 being at the same time folded over the edge of the portion 33, by a properly formed and curved folder plate 65 which, as shown in Fig. 5 is secured to the forward end of the throat plate 20 within 50 a notch or cut-away corner of the stitching plate 39, and this plate slants upwardly from its lower end which lies in the path of the downturned edge portions of the cloth, to gradually curl or fold over these 55 portions, at the same time bringing them against the underside of the part 31 of the cloth to pass onto the upper surface of the throat plate 20 and beneath the presser foot 18 to be firmly held thereby and sewed 60 together by the line of stitching 36 formed by the vertical needle 9.

To co-operate with the horizontal needle 42 in forming the proper stitching a looper 66 is secured upon the upper end of a vertical shaft 67 mounted in bearings on the

frame at the side of the flange 40 on the stitching plate opposite that at which the needle is located, said looper being arranged to co-operate with the point of the needle when the same is projected through 70 the opening in the said flange. The looper shaft 67 is arranged to rotate and move longitudinally in its bearings so that the looper will be raised above the plane of the needle at the time the needle pierces the cloth and 75 passes through the flange and so that the needle will pass through a loop of thread carried by the looper, and then as the movement continues and the looper turns, the loop of thread will be cast off the point of 80 the looper and tied up around the needle, this happening at the inner end of the stroke of the needle with the looper at the extreme rear end of its throw, then as the reverse movements take place, the looper 85 lowers and turns forward as the needle recedes, and the point of the looper picks off below the needle, the loop of thread from the eye thereof.

To secure these movements of the looper 90 in exact timed relation to the movement of the needle, rotation of the looper shaft is effected by providing an arm 68 on said shaft which is held against moving with the longitudinal movement of the shaft by 95 mounting said arm between the bearings 69 for the shaft and to operatively connect the arm to the shaft to turn therewith and at the same time permit the shaft to move longitudinally independently of the arm, a longitudinal groove 70 is provided in the shaft to be engaged by a key carried by the arm. The shaft and looper are rotated by connecting the free end of the arm 68 by 100 means of a link 71 with the end of the bar 54 which is secured to the presser bar 49 and is operated through the connecting rocker 51 by the reciprocation of the needle bar 43. The rotation of the looper is thus 105 in accurate timed relation to the operation 110 of the needle 42.

To raise and lower the looper in timed relation to the operation of the needle 42 and other part, a cam 72 is provided on the drive shaft 2 and this cam is engaged by a yoke 73 pivoted on the frame intermediate its ends with its opposite end formed to engage a grooved collar 74 secured upon the lower end of the looper shaft. The turning of this yoke upon its pivotal support by the cam will thus raise and lower the looper in 115 accurate timed relation to its turning movement and to the movements of the other parts of the machine.

With this comparatively simple construction and arrangement of parts, a sewing machine which is operated efficiently to form a flat fell seam with a single and continuous passage of the material therethrough and as the auxiliary or horizontal line of 120 125 130

stitching is formed by a straight horizontally reciprocated needle, this needle and its operating mechanism may be all located within the base of the machine below the cloth plate where it will not interfere with the passage of the work therethrough and where it may be properly mounted and lubricated.

Having thus fully described my invention, what I claim is:—

1. In a machine for forming a flat fell seam in which edge portions of material are united by a line of stitching and the united portions then folded upon the body of material and united thereto by a second line of stitching, all in a single passage of the material through the machine; the combination with needles for forming said lines of stitching arranged in angular relation to each other, and folding means for folding the material; of mechanism for operating said needles in timed relation to each other, one of said needles being positioned above the plane of the passage of the body of material through the machine and the other of said needles being positioned below said plane.

2. In a machine for forming a flat fell seam, the combination with needles for forming separate lines of stitching arranged in angular relation to each other, and folding means to fold the seam; of means for operating said needles, and a cloth plate over which the work is passed for forming the seam, said cloth plate being positioned above the plane of movement of one of said needles.

3. In a machine for forming a flat fell seam, the combination with needles for forming separate lines of stitching arranged in angular relation to each other and folding means to fold the seam; of means for operating said needles, one of said needles and its operating mechanism being positioned above and the other needle and its operating mechanism being positioned below the plane of the passage of the body of the material past said needles.

4. In a machine for forming a flat fell seam, the combination with needles for forming separate lines of stitching arranged in angular relation to each other and folding means to fold the seam; of means for operating said needles, a cloth plate over which the work is passed for forming the seam, one of said needles and its operating mechanism being located below the plane of said cloth plate.

5. In a machine for forming a flat fell seam, the combination with needles for forming separate lines of stitching arranged in angular relation to each other and folding means to fold the seam; of means for operating said needles, a cloth plate over which the work is passed for forming the

seam, one of said needles being located below the cloth plate and being a horizontal longitudinally reciprocable straight needle, and means also positioned below said cloth plate and co-operating with said horizontal needle to form a line of stitching.

6. In a machine for the purpose described, the combination of a vertically reciprocable needle for forming one line of stitching, a presser foot cooperating with said needle, feeding means cooperating with said presser foot to feed the work, and means for operating said needle and feeding means in timed relation to each other; of a needle for forming a separate line of stitching and arranged at right angles to said vertical needle and below the horizontal plane of said presser foot, feeding means, and means for operating said angularly arranged needle and feeding means in timed relation to said vertically reciprocable needle.

7. In a machine for the purpose described, the combination with a vertically reciprocable needle for forming one line of stitching, a presser foot cooperating with said needle, feeding means cooperating with said presser foot to feed the work, and means for operating said needle and feeding means in timed relation to each other; of a second needle for forming a separate line of stitching, feeding means, a presser foot cooperating with said second needle, and means for operating said second needle, presser foot and feeding means in timed relation to said vertically reciprocable needle, said second needle and its cooperating presser foot and feeding means being located below the horizontal plane of the presser foot cooperating with the vertical needle.

8. In a machine for the purpose described, the combination of a vertically reciprocable needle for forming one line of stitching, a presser foot cooperating with said needle, feeding means cooperating with said presser foot to feed the work, and means for operating said needle and feeding means in timed relation to each other; of a needle for forming a separate line of stitching positioned below the horizontal plane of said presser foot and folding means positioned between said needles, and below the horizontal plane of said presser foot.

9. In a machine for the purpose described, the combination of a vertically reciprocable needle for forming one line of stitching, a presser foot cooperating with said needle, feeding means cooperating with said presser foot to feed the work, and means for operating said needle and feeding means in timed relation to each other; of a needle for forming a separate line of stitching below the horizontal plane of the line of stitching formed by said vertical needle, a stitching plate having a part provided with an opening through which the lower needle

- is projected, folding means positioned between said needles and below the horizontal plane of the line of stitching formed by said vertical needle, and a presser foot 5 co-operating with said part of said stitching plate to clamp the work while being sewed by said lower needle.
10. In a machine of the character described, the combination with a horizontally disposed cloth plate, a vertically reciprocable needle positioned above the cloth plate, and means for operating said needle, of a horizontally reciprocable needle beneath the cloth plate, cloth guiding means 15 provided with an opening through which the horizontal needle is projected, folding means positioned between said guiding means and vertical needle to fold down-turned edge portions of the cloth guided 20 by said guiding means against the body of the cloth resting upon the cloth plate, a presser co-operating with said guiding means to hold said down-turned edge portions while being sewed by said horizontal 25 needle, and means beneath the cloth plate for operating said horizontal needle and presser in timed relation to the operation of said vertical needle.
11. In a machine of the character described, the combination with a horizontally disposed cloth plate, a vertically reciprocable needle positioned above the cloth plate, and means for operating said needle, of a horizontally reciprocable needle beneath the cloth plate, cloth guiding means 35 provided with an opening through which the horizontal needle is projected, folding means positioned between said guiding means and vertical needle to fold down-turned edge portions of the cloth guided 40 by said guiding means against the body of the cloth resting upon the cloth plate, a presser co-operating with said guiding means to hold said down-turned edge portions while being sewed by said horizontal 45 needle, feeding means to engage the down-turned edge portions of the cloth opposite said guiding means, means operable in
- timed relation to said needles and presser for operating said feeding means, and means beneath the cloth plate for operating said horizontal needle and presser in timed relation to the operation of said vertical needle. 50
12. In a machine of the character described, the combination with a vertically reciprocable needle, a horizontally disposed cloth plate, and means for reciprocating said needle across the plane of the cloth plate, of a horizontally disposed longitudinally reciprocable needle beneath the cloth plate and in advance of the vertical needle in the direction of the passage of the cloth past the needles, a stitching plate in advance of the vertical needle and in the plane of the cloth plate and provided with a downwardly extending portion having an opening through which the horizontal needle is projected in its movement, folding means positioned between said stitching plate and said vertical needle to fold downwardly extending edge portions of the cloth upwardly against the underside of the body of the cloth resting upon the cloth plate, a horizontally reciprocable presser foot co-operating with a downwardly extending portion 75 of the stitching plate to hold the down-turned edge portions of the cloth while being stitched by the horizontal needle, feeding means to engage the down-turned edge portions of the cloth opposite the downwardly extending portion of the stitching plate, looper mechanism co-operating with the horizontal needle in forming a line of stitching in the down-turned edge portion of the cloth and operating mechanism beneath the cloth plate for operating said horizontal needle, said presser foot, said feeding means, and said looper mechanism in timed relation to the operation of the vertical needle. 80
